Inventor:

Frank Frizl,
By Joshua H. Lott
his Attorney

UNITED STATES PATENT OFFICE.

FRANK FRIZL, OF CHICAGO, ILLINOIS.

PAINTBRUSH HOLDER.

Application filed January 26, 1927. Serial No. 163,616.

My invention relates to a paint brush holder, and more particularly to a paint brush holder adapted to hook over the edge of a pail or paint bucket.

5 The object of my invention is to provide a paint brush with a holder of the above indicated character which is mounted on the shank of the brush, out of the way of the user and adapted to hook over the edge 10 of paint bucket when it is desired to climb about.

Heretofore painters have carried their brushes about in their hands and paint would drip over the clothing and elsewhere, 15 or the brush might be set in a pail with the bristles down on the bottom of the pail, thus bending them out of shape and shortening the useful life of the same.

By the use of my invention such undesirable dripping of paint and destruction of 20 valuable brushes is avoided. When the painter wishes to climb about he simply hooks the brush holder over the edge of the paint bucket, where it is retained until he 25 is ready to use it again. When the work is done for the day it is not necessary to rest the brush on the bottom of the bucket, as heretofore, but the holder is hooked over the rim of a bucket and the brush hangs, 30 with bristles inside of said bucket where paint will drip into the bucket.

My invention will be best understood by 35 reference to the accompanying drawing, forming a part of this invention and in which:

Fig. 1 is an elevational view of a paint brush incorporating the preferred form of my invention.

Fig. 2 is a cross sectional view of Fig. 1, 40 taken on approximately the line 2—2 of Fig. 1 and showing its application as in use.

Fig. 3 is an elevational view of a modification of my invention, and

Fig. 4 is a side view of the modification 45 shown in Fig. 3.

In the drawing I have shown, for purposes of illustration, an ordinary paint brush, having a handle 5, a shank 6, and bristles 7. The said handle is made of wood 50 or other suitable material, and is secured into the metal shank 6 by means of suitable tacks 8, and the bristles are held into the lower side by a suitable binding material through which tacks 9 extend.

55 Below the grip portion of the brush han-

dle, and just above the metal shank, is an extension of the handle forming a portion 10 of the shank. On this portion 10 I have mounted a brush holder 11, adapted to lay down along the shank when not in use, and 60 adapted to hook over the rim 12 of a paint bucket 13, as shown in Fig. 2, for carrying it about.

The holder 11 is formed of a piece of wire 65 looped as shown in Fig. 1 to form the hook or outer portion 14, and the looped end is bent back slightly at 15 to fit down over the rim of the bucket, as shown in Fig. 2. At the shank end of the holder the two parts of the same are bent outward at 16, and extend through two bearing members 17, which are secured to the shank by suitable screws or tacks 18. Beyond the members 18, the 70 ends of the wire forming the holder are bent inwardly forming the portion 19, extending 75 into a recess 20 in the shank, as best shown in Fig. 2, and allowing the holder to oscillate in its bearings through an angle, but limited in its oscillation by the metal and wood portions of the shank, into contact 80 with which the end 19 comes (Fig. 2) when moved to its upward and downward limits respectively. The holder as mounted provides a very satisfactory means of holding the brush as shown, and the holder is so located on the shank that it does not interfere 85 with the painter's hand when the brush is being used. The holder lies down substantially flat and out of the way when not in use, but may be readily oscillated to its holding position when desired.

In Figs. 3 and 4 I have shown a modification of my invention, in which 5' is a brush handle secured to the shank 6' and having bristles 7' secured thereto as previously described. On the shank is mounted a brush holder 21, made of a piece of metal stamping and bent into the shape shown in Fig. 4. 95

The lower portion 22 is adapted to fit over the rim of a paint bucket similar to the other form of my invention, and the top portion 23 is bent slightly forward to allow the holder to be oscillated in bearings 24 to a suitable position for holding the brush. In the wooden portion 25 of the shank is provided a recess 26, into which the portion 23 of the holder extends when the holder is raised to holding position. The bearings 24 are integral with the metal portion of the shank, and through said bearings extends 105 110

suitable side members 27, integral with the holder 21.

It will be understood that many variations can be made without departing from the spirit of the invention, and I do not wish to be limited to the precise details described, but desire to avail myself of such variations and modifications as come within the scope of the appended claims.

10 I claim as my invention:

1. A paint brush holder comprising a wire formed into a loop; the end of said loop being bent downwardly for engagement over the edge of a paint bucket; hinge members 15 on the shank of the paint brush; laterally extending portions on the other end of said loop and passing through said hinge members; means extending into a recess in the shank for limiting the extent of oscillation 20 of said holder and permitting the same to

swing upwardly to a substantially horizontal position.

2. A paint brush holder comprising a wire formed into a loop; the end of said loop being bent downwardly for engagement over the edge of a paint bucket; hinge members on the shank of the paint brush; laterally extending portions on the other end of said loop and passing through said hinge members; the extreme outer ends of said laterally extending portions being bent rearwardly and extending into recesses in the shank for limiting the extent of oscillation of said holder and permitting the same to swing upwardly to a substantially horizontal position, and said holder arranged to lie substantially flat on the shank when not in use.

In testimony whereof I have signed my name to this specification.

FRANK FRIZL.
